UNITED STATES PATENT OFFICE.

ARTHUR N. AMES, OF FRANKLIN, NEW HAMPSHIRE, ASSIGNOR, BY MESNE ASSIGNMENTS, TO COMMERCIAL MACHINE COMPANY, OF FRANKLIN, NEW HAMPSHIRE, A CORPORATION OF MASSACHUSETTS.

YARN-CHANGING MECHANISM FOR KNITTING-MACHINES.

1,210,881.

Specification of Letters Patent.

Patented Jan. 2, 1917.

Continuation in part of application Serial No. 635,245, filed June 26, 1911. This application filed September 26, 1912. Serial No. 722,515.

To all whom it may concern:

Be it known that I, ARTHUR N. AMES, a citizen of the United States, and resident of Franklin, in the county of Merrimack and State of New Hampshire, have invented certain new and useful Improvements in Yarn-Changing Mechanisms for Knitting-Machines, of which the following is a specification.

10 This invention relates to knitting machines, especially of the circular type, the machine being designed particularly for knitting stockings, although I do not limit myself, in all features of my invention, to 15 hosiery-knitting machines. In the following description, however, I shall refer to stockings or hosiery, because in such articles of apparel there is more occasion than in any other article for changing the yarns or 20 threads employed.

Portions of the features of invention claimed herein are divided out from my application which became Patent No. 1,052,877, granted February 11, 1913, to which patent 25 reference may be had for description of specific means of operating the mechanism claimed herein, and to which patent reference may also be had for more complete 30 description of the purpose of the various yarns w' , w^2 , w^3 , w^4 and the times when they are severally employed.

The principal object of the invention claimed herein is to provide improved mechanism for changing the yarn or thread to 35 simplify and facilitate the operation of the knitting machine. To this end the invention consists in the improvements which I shall now proceed to describe and claim.

Of the accompanying drawings, Figure 1 40 is a side elevation of a complete knitting machine embodying my present improvements; Fig. 2 is an elevation of the mechanism at the top of Fig. 1, on a larger scale, and showing also the driving mechanism 45 therefor; Fig. 3 represents a section on line 3-3 of Fig. 1, but enlarged and the thread cops removed; Fig. 4 is a view similar to a portion of Fig. 3; Fig. 5 represents an elevation of the mechanism shown in Fig. 3; Fig. 6 is a detail view of a portion of the mechanism shown in Fig. 5, partly broken 50 out; Fig. 7 represents a section on line 7-7 of Fig. 3; Fig. 8 is a plan view of the latch

ring and the members coöperating therewith, on a larger scale than Fig. 1; Fig. 9 is a detail sectional plan of some of the mechanism shown in Fig. 8; Fig. 10 represents a section on line 10-10 of Fig. 8; Fig. 11 is a detail plan of the presser plate; Fig. 12 is a view similar to Fig. 3, partly broken out to illustrate further details; Fig. 13 represents a section on line 13-13 of Fig. 12; Fig. 14 represents a section on line 14-14 of Fig. 2, and a detail plan of parts to the right of said line; Fig. 15 represents a section on line 15-15 of Fig. 2.

Similar reference characters indicate the same or similar parts in all the figures.

Referring first to Fig. 1, the top of the main frame is indicated at 15, said frame 70 supporting a fixed ring 16 in or on which the cam cylinder 17 is rotatably mounted. A post 18 rotates with the cam cylinder and communicates the motion thereof to the ring 101, as hereinafter described. The latch 75 ring is indicated at 19, said latch ring being pivotally connected at 22 to an arm 21 of the cam cylinder, the other side of the latch ring being supported by an arm 20 of the cam cylinder. Rising from the top 15 of the main frame is a bracket 23 having two posts 24, 25 which support a bracket 26 having a bed-plate 27 for the yarn-introducing devices. For a detail description and illustration of the parts so far referred to, reference may be had to my said patent. The bed-plate 27, however, supports a gear housing 28 of the type illustrated and described in my concurrently filed application Serial No. 722,514.

The twister indicated at 29 herein (Figs. 1 and 2) is driven through the medium of a shaft 30 having a disk 31 which is adapted to be shifted into and out of contact with a disk 32 on the upper end of a vertical shaft 33, the latter having a foot disk 34 bearing upon the periphery of a drive disk 35 secured to a continuously operating shaft 36. The twister-rotating shaft 30 has its rear end supported in a bearing carried by a lever 37 which in turn is controlled through the medium of a lever 38 and a pattern-controlled rod connected to said lever 38. When the lever 38 is oscillated or swung in one direction it separates the disk 31 from disk 32, and then a toe of the lever 37 reaching

under the disk 32 lifts said disk and the shaft 33 so as to separate the foot disk 34 from the constantly rotating disk 35. When the lever 38 is shifted in the other direction it 5 yieldingly forces the lever 37 in a direction to bring the disk 31 down upon the disk 32 and to press the latter, shaft 33, and the foot disk 34, down to cause the twister to positively rotate in the manner described in 10 my said application.

As the mechanism so far described is not claimed herein, further description or illustration thereof will not be necessary.

The guide ring 39 is supported as hereinafter described. Extending down through the center of said ring 39 is a hollow shaft which is telescopic. The upper member or tube 40 of this shaft is rotatably supported by an extension of the plate 27 at the top of the machine (Figs. 1 and 2). The lower tube member 41 is longitudinally slidable in the upper member 40, the latter having a vertical slot 42 which receives a pin 43 projecting from the lower tube or member 41 (Figs. 1 and 4). There is sufficient friction provided for to hold the lower tube 41 when it is slid upwardly to enable the latch ring to be raised. The main thread w^1 and the reinforcing thread w^2 , when the latter is 20 employed, pass downwardly through the hollow shaft, and since the lower end of the latter is, when extended or lowered as shown in Fig. 1, not far above the latch ring, said thread or threads cannot at any time interfere with the thread or threads w^1, w^2 when the latter are employed for double-course knitting. The vertically elongated slot 42 facilitates the "threading up" by enabling a suitable instrument to be inserted through 30 said slot and engaged with the thread or threads leading from the upper take-up so as to draw said thread or threads down to the needle.

As shown in Fig. 8, the latch ring 19 is 40 provided with a throat plate 45 and a guide eye 46 such as in my said patent. The presser plate 47 is supported by hangers 48, which, as shown by comparing Figs. 1 and 50 8, are arched to permit the needles to pass thereunder. Said presser plate carries suitable thread clamps, as indicated at 49 and 50, and the convex edge thereof is provided with hooks 51.

The presser-foot 47 prevents the heel portion 55 of the stocking that is being knitted from bulging up so as to interfere with the thread-feeds. The hooks 51 confine the idle thread so that when the thread guide of this 60 idle thread is thrown into operative position, the thread controlled thereby will be in proper position to pass through the gateway or slot and properly connect with the needles. Said hooks 51 also prevent the loose or idle thread from passing in either direction 65 behind the presser-foot 47, or to what

is termed the center of the machine, said hooks preventing the thread from being held up above the plane of needle action.

To alternately change the positions of the arms which have the thread eyes for the changing of the threads w^1, w^2 , I provide a slide supported upon arms 52 of the latch ring 19 (Fig. 8). Said arms support a segment slide 53, each end of which is cut away to form shoulders 54, 55, with a recess 56 near the shoulder 55. Supported by the ring 19 are two pivot pins 57, 58, on which are mounted the arms 59, 60, carrying thread guides 61, 62. (See also Fig. 12). The short arms 63, 64 of the arms 59, 60 have 80 pins 65, 66. These rocking arms also have stop arms 67 adapted to contact with stop shoulders 68 of the ring 19 to limit the oscillations of the arms 59, 60, in one direction. It will now be understood that when the 85 segment slide 53 is shifted in the direction of its arrow from the position shown in Fig. 8, the recess which engages pin 65 will first swing the arm 59 and its eye or guide 61 outwardly to operative position, 90 further motion of the slide in the same direction causing said pin 65 to ride along the surface between the said recess and the shoulder 54. At the same time, the pin 66 of the other arm 60 is riding along the surface until the shoulder 55 contacts with said 95 pin 66, after which continued movement of the slide 53 in the direction of its arrow will swing the arm 60 in the direction of its arrow so as to carry its guide eye 62 100 inwardly, but to inoperative position. Of course, the reverse motion of the slide 53 back toward the position shown in Fig. 8 will first swing the arm 60 outwardly and then swing the arm 59 in the direction of 105 its arrow back to the position shown in said Fig. 8.

The reciprocating motions of the segment slide 53 are imparted by a lever 69 pivotally supported at 70 and having a pivotal connection at 71 with one end of a link 72, the other end of which link is pivotally connected at 73 to the slide 53. To impart the necessary motion to the lever 69, another arm of said lever has a pin-and-slot connection 74 with a slide 75, the outer end of this arm of the lever moving to one side or the other of a yielding presser or spring 76 so as to hold the lever 69 either in the position shown in Fig. 8 or in the position 110 to which it is shifted when the slide 53 is moved to its other extreme. For present purposes it is not necessary to explain the details of the mechanism for operating the slide 75 so as to oscillate the lever 69, the 115 same being fully illustrated and described in my said patent. It may be explained, however, that the automatically shiftable cam lever 77 shown in Fig. 1 acts upon the vertically movable pin 78 carried by the 120 125 130

cam cylinder, so that the latter, through connections not shown herein, actuates slide 75 to shift the yarn or thread-changing arms 59, 60 in the manner described.

The latch ring 19 is provided with a throat plate 79 having a slot 80 for the passage of the threads when the yarn is changed. The arms 59, 60 have gates as illustrated and described in my said patent, but they do not entirely close the slot 80, or at least not sufficiently so to guide or hold the thread. To attain this last mentioned result I employ an oscillating member 81 having two arms

(Figs. 8, 9 and 10) pivoted at 82 to a protecting arm 19^a of the latch ring, the outer arm of the member 81 having a somewhat U-shaped cam slot 83 which is engaged by a pin 84 of the slide 58. The slot or opening 83 is formed to present recesses 85, 86 with which the pin 84 may contact alternately, as the slide 58 oscillates, so as to oscillate the member 81 on its pivot. Said member 81 is formed with a notch 87 and with horns 88, 89 at the opposite ends of said notch. The vibratory or shiftable thread holder or guide 81 is reversed or swung from side to side each time that the slide 58 is operated. The opening or slot 83 in the member 81 is so shaped that the notch 87 is in register with the slot 80 of the throat plate 79 when either arm 59 or 60 is moving in the direction of its arrow in Fig. 8, so that the thrown-out thread can pass in through slot 80 of the throat plate. At all other times, one or the other of the horns 88, 89 is in position to hold the thread from rising up through slot 80 over the heads of the needles, and at the same time exclude the latches of the needles from the slot 80. The recess 87 of the member 81 presents a guide or holder for the thread, one horn or the other crossing the lower part of the slot 80 (Fig. 10), and the outer edge of one horn or the other is always in position to guide the latches of the needles past said slot, if any latch gets into the closed position shown in Fig. 10 and has a tendency to then swing outwardly.

The oscillating member 81 and its horns 88, 89, constitute a latch protector. It causes the threads to be held down in the latch ring 19, and said horns alternately bridge the opening in the slot in said latch ring so as to prevent the latches of the needles from ever dropping down. In other words, this latch protector provides means which will prevent the thread (if a loop of slack thread is thrown up) from getting over the top of the needles. The purpose of the oscillating member 81 and its arms, is not only to guide the thread or yarn or hold it from rising up through slot 80 over the heads of the needles, but also, by bridging the lower portion of the slot or opening 80, to guard against liability of breaking the latches of the needles when the needles are down and

in action. The gates 90 presently described serve the purpose of preventing breaking of needle latches when the needles are up and out of action, while one or the other of the two arms of the oscillating member 81 prevent breaking needle latches when the needles are down. So far as I am aware, I am the first to provide different means in two different elevations for bridging the slot or opening of a latch ring to avoid any liability of breaking needle latches not only when they are up and out of action but also when they are down and in action.

Each arm 59, 60 has a gate to close the portion of slot 80 above the plane of the oscillating member 81, so that, when the needles are elevated to their highest positions, the latches cannot catch in said slot. Each gate comprises a plate 90 having an inner flange 91 and an outer flange 92. The plate 90 is pivoted to its arm 59 or 60 at 93 and has a slot 94 through which a screw 95 passes into the arm whereby the plate and its flanges may be adjusted relatively to its carrying arm. Obviously, each plate 90 might be made of two pieces instead of one, if desired. As the arms 59, 60 swing as hereinbefore described, the flange 91 of one plate 90 and the flange 92 of the other plate 90 alternately occupy edge to edge positions as indicated in Fig. 8.

As shown in Figs. 1, 3, 4 and 5, the guide ring 39 is carried by an arm 100 suitably supported by the bracket 23. Within the ring 39 is a ring 101 (Figs. 12 and 13) having an arm 99 (Fig. 7) which is engaged by the post 18 rising from the cam cylinder so that said ring 101 partakes of all movements of the cam cylinder. Mounted within the ring 101 is a disk-shaped lock carrier 102 (Figs. 3 and 15), said carrier having a hub 103 (Fig. 7) secured to the lower end of the tubular member 40 of the hollow shaft. Also secured upon the tubular member 40 is a hub 105 having arms 104, two of the latter supporting posts 106 for the supply of thread. Fitted to parallel ways of the carrier 102, and between said carrier and the lower end of 105, is a lock slide 107, which, as hereinafter described, is moved to unlock when the clutch of the driving mechanism is shifted to produce the heel or split foot of a stocking, and is shifted to lock when the clutch is shifted for rotary or round-and-round knitting. The slide 107 is provided with eyes 108 which are, of course, in register with similar apertures above and below them formed in arms 104 and in carrier 102, as shown in Fig. 13, so as to permit the threads w^3 , w^4 to pass, these latter, however, always passing, as shown in Fig. 1, outside of the lower extension member of the tubular shaft so as to never conflict with each other or with the main thread w^2 or the reinforcing thread w' .

To cause the slide 107 to automatically shift to lock, it is provided with a tongue 109 having a cam-shaped outer end which is adapted to engage with a lug 110 of the guide ring 39 so as to shift the slide toward the right in Fig. 4. A spring 11 engaging a pin 112 of the slide 107 yieldingly pushes said slide in the same direction. The slide 107 is formed with a downwardly depending lug 113 adapted to enter a recess or keeper 114 in the ring 101. (See Figs. 4 and 13). The purpose of the cam tongue 109 and the lug 110 is to supplement the action of the spring 111 to render it certain that the lug 113 will enter the recess or keeper 114 at the proper time. During reciprocating knitting the slide 107 is locked to the guide ring 39, as presently described, while during rotary or continuous knitting the slide 107 is locked to the ring 101. As the slide 107 cannot rotate independently of the carrier 102, owing to the parallel ways supporting it, and since the hub of said carrier 102 and the hub of the thread carrier arms 104 are secured to the tubular shaft member 40, the said tubular shaft 40 and the thread carrier arms 104 and the lock carrier 102 must always either reciprocate or rotate or remain stationary together.

The slide 107 has a lock tongue 115 opposite the cam tongue 109, said tongue 115 being adapted to contact with a stop shoulder 116 (Figs. 4 and 13) carried by a slide 117 so that when said slide 117 and its shoulder 116 are in position nearest the axis of movement of the carrier 102, rotation of the latter will be stopped. The slide 117 is provided with a cam block 118 (Fig. 3) which is adapted to be engaged by an elbow lever 119 to advance said slide to stopping position in opposition to a suitable spring. The elbow lever 119 is connected by a link 120 with one arm of an elbow lever 121, the other arm of which is connected to a rod 122 (Figs. 3 and 5), said rod being connected to the same pattern-controlled mechanism that changes the yarns or threads, as explained in my said patent. To prevent rebound of the lock carrier and its slide 107 when the tongue 115 contacts with the stop shoulder 116, I provide a latch 123 pivoted to the slide 117, said latch having a portion adapted to be engaged by the tongue 115 as the latter passes around so as to lift the latch and let the tongue 115 pass, said latch dropping behind the tongue 115 as soon as the latter reaches stop shoulder 116. Secured to the upper tube 40 (Fig. 2) is a hub 124 having ears provided with thread eyes 125 (Fig. 15) and having arms 126 provided with thread eyes 127. Slidably mounted on the tube 40 above the hub 124 is a sleeve 128 having an annular groove 129 engaged by a yoke 130 (Figs. 2 and 14) of a lever 131 pivoted at 132 to an arm 133 of bracket 26. The other end of the lever 131

is provided with cams 134, 135 engaged by a pin 136 projecting from controlling lever 38. As described in my concurrently filed application Serial No. 722,514, the controlling lever 38 affects the operation of the twister 29 for the reinforcing thread, and the cutter 137 for said thread, while the take-up 138 is controlled by a bell crank lever 139. As the bell crank lever 38 swings, its pin 136 contacts with the cams 134, 135 to actuate the lever 131 in opposition to a spring 140, to cause said lever to hold sleeve 128 in either one of two positions of elevation to control the tensions for the two threads w^3 , w^4 , which pass from the bobbins or cops up through the eyes 127, across the upper surface of disk-shaped portions of the arms 126, and down through the eyes 125. To bear on each thread with automatically variable pressure, I employ a tension pad 141 (Figs. 1, 2 and 15) carried by a lever 142 pivoted at 143 to arm 126 and having its other end pressed upwardly by a spring 144 mounted in a recess in arm 126, an adjusting screw 145 being provided to vary the pressure that the spring may cause the pad 141 to have on the thread under it, when permitted to act by the mechanism herein-after described.

Another lever 146 is mounted on each pivot 143 and has its long arm engaging the under side of the flange 147 of sleeve 128, each lever 146 being caused to follow vertical movements of said sleeve, by a spring 148 mounted in a recess or socket in arm 126, the force of said spring being variably controlled by an adjusting screw 149. Each lever 146 is provided with lugs 150, 151 near its fulcrum, adapted to alternately contact with the lever 142 below it, to rock the latter.

The operation of this portion of the machine, and the timing of the movements imparted to the several elements thereof, is such that when the machine is doing even reciprocating knitting the tension pads press on the threads with only the force of springs 144, this being the operation indicated in Fig. 2. By the term "even reciprocating knitting", I mean the operation when reciprocations are equal in length or distance, as distinguished from the narrowing and widening at the heel and toe. When the elbow lever 38 is shifted in the direction of the arrow so that its pin 136 is off from cam 135, which is when the machine is knitting continuously or doing plain circular knitting, the spring 140 actuates lever 131 so as to depress sleeve 128 and the long arms of levers 146, the lugs 151 of the latter acting on levers 142 to raise pads 141 and relieve the threads of all tension. The spring 140 is, in practice, of sufficient strength to overpower the springs 144, 148, when permitted to do so by the pin 136. When the elbow lever 38 is shifted in the opposite di-

rection so that its pin 136 is on cam 134 of lever 131, which is when the machine is narrowing and widening, at heel or toe of the stocking, the sleeve 128 is raised to its highest position, and then the two springs 148 supplement the tension-applying power of springs 144 by causing the lugs 150 of levers 146 to bear down on the portions of levers 142 between their fulcrums and the pads 141, thereby causing the pads to bear on the threads heavily.

As has been explained, the tension is off from the threads w^3 , w^4 when pin 136 is off from the cams of lever 131. At this time, 15 it is essential that the spring take-up arms 152, shown in Fig. 12 and presently described, shall be thrown in so that the thread eyes 153 thereof will be near the eyes 108 of arms 104, and said take-up arms remain out 20 of action. I will now describe the structure and operation of these spring takeups, referring especially to Figs. 3, 5, 6, 7, 12 and 13.

Mounted on the hub 105 (Figs. 5 and 7) 25 is a sleeve or collar 154 having a notch 155 in its lower edge. A pin or lug 156 of slide 107 (see also Fig. 4) engages said notch so that the reciprocations of the slide will impart oscillating rotary movements to the collar 154. Said collar has arms 157, to each of which is pivoted a slide rod 158, the outer end of which passes through a bearing 159 (Fig. 12) supported by two of the arms 104. Each spring take-up 152 is pivoted to 35 an arm 104 at 160 and has a heel or short arm 161 to which is connected a spring 162 which causes the take-ups to follow movements of the arms 157 of the collar 154 so that when the latter is shifted by the slide 40 107 (which occurs when the machine is changing from reciprocating to circular motion), the eyes 153 are thrown in close to the eyes 108, thus permitting the thread or yarn to pass so straight through the eyes as 45 to have the slightest possible friction tension in said eyes.

As shown in Fig. 6, the upper edge of the collar 154 is cut away to form a cam 163 which is engaged by the lower end of a vertically movable rod 164, the upper end of which (Fig. 2) engages the sleeve 128. When the machine is changing from circular to reciprocating motion, the cam 163 imparts to the rod 164 sufficient motion to raise the 55 sleeve 128 to the same point that results from the movement of pin 136 on to cam 135, which, as has been explained, causes the pads 141 to bear on the yarns or threads with the pressure of the single springs 144.

60 In Fig. 10 a needle is shown in lowered position. When the needle is raised, its latch might become displaced and rest on top of the latch ring 19. To guard against any such displaced latch being broken by lateral 65 contact with a gate when approaching the

latter, each flange or gate 91, 92 is beveled laterally and upwardly, as shown at 165 in Fig. 10, so that such bevel will deflect a displaced latch back to upright or closed position.

Having described my invention, I claim:

1. A knitting machine having yarn changing mechanism including yarn feeds, means for reciprocating said feeds, a guide ring, and a vertically adjustable cylindrical member normally extending below said ring to separate the yarns leading to the needles during reciprocating knitting.

2. A knitting machine having yarn changing mechanism including yarn feeds, means for reciprocating said feeds, a guide ring, and a telescopic tube having its lower member normally extending below said ring to separate the yarns leading to the needles during reciprocating knitting.

3. A knitting machine having yarn changing mechanism including yarn feeds, means for reciprocating said feeds, a guide ring, and a telescopic tube having its lower member normally extending below said ring, to separate the yarns leading to the needles during reciprocating knitting, the upper member having a vertical slot.

4. In a knitting machine a latch ring having a slot for the passage of threads, a yarn changer comprising a pair of thread guides pivotally mounted on vertical axes at opposite sides of said slot, the guides being movable through said slot, a segment slide, means for actuating said slide and connections whereby said slide will swing the thread guides in opposite directions.

5. In a knitting machine a latch ring having a slot for the passage of threads, a yarn changer comprising a pair of thread guides pivotally mounted on vertical axes at opposite sides of said slot, the guides being movable through said slot, a segment slide, means for actuating said slide, and connections whereby said slide will swing the thread guides in opposite directions, said guides having gates adjacent the thread passages.

6. In a knitting machine, a latch ring having an opening for the passage of yarn, yarn changing mechanism adjacent said opening, and pivotally mounted gates movable in a plane toward and from the needles to close a portion of said opening, said gates having laterally beveled portions to deflect displaced needle latches back to operative positions.

7. In a knitting machine, a yarn changer comprising a pair of pivotally mounted thread guides, a segment slide, means for actuating said slide, and connections whereby said slide will swing the thread guides in opposite directions, said guides having gates adjacent the thread passages, said gates having laterally beveled edges.

8. A yarn-changing mechanism for knitting machines, comprising a pair of arms mounted on vertical pivots and having thread guides movable in a substantially horizontal plane toward and from the needles, and a segment slide for actuating said arms and their guides.

9. A yarn-changing mechanism for knitting machines, comprising a pair of arms mounted on vertical pivots and having thread guides movable in a substantially horizontal plane toward and from the needles, a segment slide having means for actuating said arms and for locking them in 10 or out of position, and means for actuating 15 said slide.

10. A yarn-changing mechanism for knitting machines, having a latch ring provided with a slot, and an oscillating thread guide 20 or holder having horns adapted to alternately cross said slot.

11. A knitting machine having a latch ring provided with an opening for the passage of yarn, and yarn changing mechanism comprising a pair of arms mounted on vertical pivots on opposite sides of said opening, said arms having thread guides movable in a substantially horizontal plane through 25 said opening, each arm having a plate provided with two flanges forming gates for 30 said opening.

12. A knitting machine having a latch ring provided with an opening for the passage of yarn, and yarn changing mechanism 35 comprising a pair of arms mounted on vertical pivots on opposite sides of said opening, said arms having thread guides movable in a substantially horizontal plane through 40 said opening, each arm having a plate adjustably connected to it, said plates having flanges forming gates for said opening.

13. A knitting machine having means for producing continuous or reciprocating knitting, yarn changing mechanism, a rotatably 45 supported bobbin carrier, means for locking said carrier to hold it stationary, and means for simultaneously controlling the yarn changing mechanism and the bobbin carrier.

14. A knitting machine having means for 50 producing continuous or reciprocating knitting, yarn changing mechanism, a rotatably supported bobbin carrier, a lock slide for said carrier, means for rotating the carrier when unlocked, and means for shifting said 55 slide to unlock the carrier for continuous knitting and to lock it for reciprocating knitting.

15. A knitting machine having means for 60 producing continuous or reciprocating knitting, yarn changing mechanism, tension devices for the yarns, and means for auto-

matically controlling said tension devices to cause them to act with greater effect when producing even reciprocating knitting than when producing continuous knitting, and 65 with still greater effect when reciprocating during narrowing and widening.

16. A knitting machine having means for producing continuous or reciprocating knitting, yarn changing mechanism, tension devices for the yarns, and means for automatically controlling said tension devices to cause them to act with greater effect when producing even reciprocating knitting than when producing continuous knitting, and 70 with still greater effect when reciprocating during narrowing and widening, said controlling devices including compound spring-actuated levers and connections whereby one 75 supplements the action of the other. 80

17. A knitting machine having means for producing continuous or reciprocating knitting, yarn changing mechanism, a rotatable yarn supply, means for automatically varying the tension on the yarns, pivoted take-up arms, springs normally acting to throw said arms outwardly, and means for swinging said arms in opposition to their springs and holding them in inoperative positions during continuous knitting, said means for 85 swinging the arms comprising rods for acting on said arms, a collar having arms to which said rods are connected, and means for automatically oscillating said collar.

18. A knitting machine having a latch ring 90 provided with an opening, a pair of devices for bridging said opening, said devices being pivotally supported at a point outside the inner wall of the latch ring, and means for alternately shifting said devices 100 across said opening from opposite sides thereof.

19. A knitting machine having a latch ring provided with an opening, means for bridging the upper portion of said opening, separate means for bridging the lower portion 105 of said opening and means for shifting said bridging means.

20. A knitting machine having a latch ring provided with an opening for the operation 110 of yarn guides, gates for closing those portions of the opening through which the yarn guides operate, and supplemental means below said gates to cross the lower part of the opening. 115

In testimony whereof I have affixed my signature in presence of two witnesses.

ARTHUR N. AMES.

Witnesses:

C. F. BROWN,
PETER W. PEZZERI.
